UNITED STATES PATENT OFFICE

BYRON M. CHENEY, OF CHICAGO, ILLINOIS

TIE-PLATE

Application filed July 2, 1928. Serial No. 289,649.

My invention relates in general to means for securing railroad rails to ties, and in particular to an improved tie plate adapted for use in this connection with the method for producing such improved tie plate.

The present standard means for securing rails to ties is by means of a standard type of headed spike which is driven into the ties and engages over and contacts with the upper surface of the rail base so as to secure the rail tightly against the ties. It is customary on a properly equipped track also to employ a tie plate under each rail on each tie, and these aid in preventing spreading of the rails and for preventing cutting of the ties by the rail bases.

It is a well known fact that when traffic moves over a track there is an upward and downward movement and some forward movement of the rails which is commonly known as a wave motion. This motion has a tendency to pull the spikes out of the ties and it is common practice to repeatedly drive them back into place with the result that the holding power of the tie fibre is soon lost and the spikes become so loose that moisture seeps in around them and causes a rotting of the ties. There are many other disadvantages connected with this type of installation, and I have overcome many of these objections by introducing a novel spike on which a patent, Number 1,604,806 was granted me on October 26, 1926. The use of my spike with a standard equipment has resulted in a great improvement in track installation, but I now propose modification of other portions of the equipment particularly the tie-plates to carry out to a still greater satisfaction the improvement in railroad track installations. I am aware that any such improvements should be made preferably without increasing the ultimate cost of an installation.

Accordingly the principal object of my invention is the provision of an improved railroad track installation.

Another object is the provision of a railroad track which will require a minimum of upkeep.

Another object is the provision of a tie

plate adapted to correct the difficulties outlined above, and with which a standard type of spike may be employed.

Another object is the provision of an improved method for producing such a tie plate. 55

Another object is the provision of improved means for positively spacing the spike head from the top surface of the rail base.

Another object is the provision of a tie plate adapted to be employed in combination with a standard spike to permit normal wave motion without straining the relative positions of rail spikes, tie plates, or ties. 60

Other objects and features of the invention will be apparent from a consideration of the detailed description taken with the accompanying drawings, wherein— 65

Fig. 1 is a fragmentary plan view of a railroad rail installation showing my improved tie plate in position; 70

Fig. 2 is an irregular sectional view taken along line 2—2 of Fig. 1;

Fig. 3 is a fragmentary view showing a modification;

Fig. 4 is still another modification, and 75

Fig. 5 shows another way of forming a spacing lug.

While I have provided an improved method for manufacturing a tie plate it is believed that the steps of the method and the purpose thereof will be more manifest from a preliminary understanding of the article itself and the manner in which it is employed in actual use with other equipment. 80

Referring first in a general way to the use of the tie plate of my invention it is understood that the usual ties A are employed with suitable rails B and spikes C. Between the rail and ties the tie plate D is placed and it is particularly with respect to this member that the present invention is directed. 85

This tie plate is of rectangular shape and in all usual respects except as will be pointed out, may resemble any of the present type of tie plates, so that the shape and general character thereof are simply illustrative. 95

The tie plate to which my invention is now particularly directed may be adapted for use with standard or special equipment, and may still be made to accomplish the principal 100

object set out in the present invention including the allowance of sufficient space between the spike head and rail base to allow normal wave motion. The standard spikes employed may vary somewhat, as it is well known that in various parts of the country, the exact dimensions of the head, shank, etc., may be found to be a little different, and still be the spike considered for all practical purposes. For example some spikes are provided with a heel extending a considerable distance from the shank somewhat as shown in Figs. 1 and 2; while other spikes have practically no heel, being of the general shape shown in Fig. 4. Here one of these types may be considered as a standard spike, but the specific manner in which they will be used with my invention will vary as will be pointed out as the description proceeds.

In the tie plate of my invention I provide a number of lugs adapted to lie either up against or adjacent the outside edge of the rail base. These lugs are formed preferably from the material of the tie plate and are in general adapted to accomplish two purposes, namely to control the spacing of the rails with respect to each other, and to space the head of the spikes away from the upper surface of the rail base by limiting the degree of insertion of the spikes into the ties.

Considering the main form of Figs. 1 and 2 I provide lugs 10—10 and other lugs 11—11. All of these lugs are formed up from the material of the tie plate and are so arranged that in the forming process apertures are made through the tie plate. The apertures adjacent the lugs 10 are not necessarily applied to any use, but the lugs themselves serve the purpose of preventing any possible sidewise movement of the rails with respect to the tie plates. In other words they prevent spreading of the rails and for this reason may be placed only on the outside of the tie plate; but I prefer the arrangement shown wherein the rail is protected from shifting in either direction, and the tie plate is adapted to universal application without regard to the direction in which it is shifted. The apertures adjacent the lugs 11, however, are formed large enough to receive the shanks of the spike C and the lug is so formed as to engage the heel of the type of standard spike shown to prevent the bottom of the spike head from engaging against the upper surface of the rail base. I form this lug 11 so that with standard spikes the space between the spike head and upper surface of the rail base will be about $\frac{1}{8}$ in. but this may be varied to suit different types of rails and different operating conditions, the thing to be borne in mind being that this clearance should be enough simply to allow normal wave motion and while $\frac{1}{8}$ in. is about right for most equipment which is now used in main

lines, it may be found advisable as stated to employ a greater clearance.

The specific structure shown in Figs. 1 and 2 is illustrative of what I now consider the best form of the invention, but the principles therein disclosed may be employed with a modified structural form and in Figs. 3 to 5 inclusive I illustrate certain of these modifications.

In Fig. 3 the tie plate is formed to adapt it for using a spike having a stop 12 formed at the heel thereof somewhat similar to the stop shown in my patent above referred to. The stop 12 in this instance, however, is of insufficient length to support the head of the spike a sufficient distance away from the upper surface of the rail base and for this reason a lug 11' is provided of lesser height than the lugs 11 shown in the main figures. In other words the heel stop 12 and lug 11' together will equal the height of the stop provided on my patented spike where the same clearance is to be provided to allow normal wave motion.

These spikes shown in Fig. 3 are in certain respects standard although they are not in near as wide use as the spike shown in the other embodiments. A stop similar to 12 is provided in these spikes to allow for the thickness of the rail base, so that when the stop is down flush against the tie plate, the spike head will engage against the top of the rail base. If spikes of this character are used it appears clear that the upstanding lug 11' would extend above the tie plate a distance equal to the "wave motion" clearance which I am seeking to provide.

While I prefer to employ two sets of lugs on the tie plate, one set for spacing the rail and the other set for spacing the spikes, I may utilize a single set of lugs to accomplish both functions. For example as shown in Fig. 4 a lug 10' may be formed to lie against the edge of the rail base as illustrated, and the adjacent aperture formed of sufficient size to receive a spike shank for engaging over the rail base. This same lug 10' therefore also serves as a stop to space the head of the spike away from the rail base in the same way that is accomplished by the lugs 11. In other words the lug 10' is in effect a dual purpose lug and accomplishes a double spacing action so that only half as many of these lugs are necessary as when employing the style previously described.

The form of Fig. 4 is of particular utility when spikes of the character shown are used. This is a strictly standard spike, there being probably more of this kind of spikes in use than any other with the possible exception of the spike shown in Fig. 2. The spike of Fig. 4, however, appears to me to be gaining in popularity among railroad men as it can usually be made somewhat more economically than the spike shown in the main embodiment.

With the arrangement of Fig. 4 I may also employ another species of spikes which has been in somewhat extensive use, this spike having a depending stop under part of the head in a position so that it would engage against the top of the extension or lug 10'. If this species of spike were used it would of course be possible to make the extension on the tie plate somewhat lower, care being taken however to maintain that it was of sufficient height to support the edge of the rail base with positive security.

Instead of upturning the lug at right angles to the tie plate as shown in Figs. 1 to 4, these lugs may be formed in a number of different ways to secure the same result, it being necessary simply to produce the lugs from the material of the tie plate by a forming process. It is preferred of course to utilize a process which can be carried out by a simple stamping operation but the invention is not limited necessarily to any particular method of producing the tie plate. One form which the lug may take is shown in Fig. 5 wherein an upstanding portion 110 is formed so that substantially no apertures result, and the desired height, strength, and other features of the formed section of metal are obtained. While I prefer when using this form to limit it to use as an anti-spreading device, I may also employ it to engage the spike heads after the fashion of the lug 11.

In forming my improved tie plate the body portion thereof is first produced and this is done in any of the usual ways, preferably by rolling strips of suitable cross section and then cutting plate bodies of the proper size from the material of the strips. I next form the spike holes and the holes adjacent the lugs 10 where this form of lug is used, and at the same time produce the lugs 10 and 11 from the material of the tie plate. This method is carried out for any of the types of lugs or stops shown. In forming up these holes or stops it may be necessary to resort to a two-step method, this depending upon the particular machine shop practice in connection with the operation of punch presses, but from the standpoint of production the step of forming up the stops and producing the spike holes is a single operation as it entails only a single handling of the article.

While I have described many features of the device of my invention and described the method of producing the same, these features and the method are illustrative and the invention is limited only by the scope of the appended claims.

What I claim as new and desire to protect by Letters Patent of the United States is:—

1. The method of manufacturing a tie plate adapted to support railroad spike heads away from a rail base which comprises producing a standard plate body and then form-

ing projections on said plate body for engaging under the spike head.

2. The method of manufacturing a tie plate which comprises producing a standard imperforate tie plate body, punching holes in the tie plate body for receiving track spikes, and forming of the material taken from the holes upturned projections adapted for spacing the rails and for limiting the degree of insertion of the track spikes into the ties.

3. In a tie plate a tie plate body for insertion between a rail and a tie, with spike receiving apertures therein, and stops formed from the material taken from the aperture to limit the insertion of the spikes and keep the head clear of the rail to allow wave motion of said rail.

4. In a tie plate a tie plate body for insertion between a rail and a tie with spike receiving apertures, and stops comprising sections of the tie plate body turned upwardly from the adjacent apertures and adapted for engaging under the spike head to keep said spike head clear of the rail to allow wave motion of said rail.

5. In a tie plate a tie plate body for insertion under a rail base and above a tie, said tie plate body having spike receiving apertures along the edge of the rail base with stops formed of the material taken from the spike apertures and adapted for engaging under the heel of the spike head for preventing the spike from engaging against the upper surface of the rail base, and separate spacing lugs formed of the material of the tie plate body and placed so as to engage along the outside edge of the rail base for spacing said rail.

6. The combination with a tie plate adapted for insertion under a rail and having projections thereon, of a spike having a head and means forming a part of the head for engaging said projection to maintain the spike head away from the top of the rail base.

7. The combination with a tie plate adapted for insertion under a rail and having projections for preventing spreading of the rails, of a spike having a head, and with means forming a part of the head for engaging against one of said projections for positively preventing driving the spike into contact with the rail base so that free wave motion is permitted.

In witness whereof, I hereunto subscribe my name this 30th day of June, 1928.
